SEWER CONSTRUCTION

Filed Aug. 31, 1927

UNITED STATES PATENT OFFICE

ROBERT B. TUFTS, OF ATLANTA, GEORGIA

SEWER CONSTRUCTION

Application filed August 31, 1927. Serial No. 216,626.

This invention relates to the construction of sewers from reenforced concrete or cementitious material and has for its object the provision of means and a method of proceeding whereby a sewer may be built rapidly at a low cost and when finished, will be braced against collapse and will not be subject to leakage. The invention is illustrated in the accompanying drawing and will be hereinafter 10 fully described, and it consists in certain novel features which will be particularly pointed out in the appended claims.

In the drawing, Figure 1 is a perspective view of a portion of a sewer constructed according to the present invention;

Figure 2 is an enlarged transverse section of the same;

Figure 3 is an enlarged detail perspective view of one of the joints in the side walls seen 20 in Fig. 1;

Figures 4 and 5 are plan views showing other forms of joints;

Figure 6 is a detail elevation, and

Figure 7 is a section showing a variation in 25 the joint between the side and the bottom of the sewer.

In carrying out the invention, I provide a plurality of precast slabs 1 of reenforced concrete which are employed to form the sides of the sewer, and are preferably provided in 30 their side edges with grooves 2 adapted to register when the slabs are set up edge to edge. A recess or channel is thus formed into which grout, indicated at 3, is poured so as to key the adjacent slabs together and seal the joints 35 against leakage of the matter flowing through the sewer. Each slab is provided on one face with a projecting ledge 4 at an intermediate point in its height for a purpose which will 40 presently appear, it being noted that the under surface of the ledge is at a right angle to the face of the slab while the upper surface of the ledge is inclined and merges into the face of the slab. While I have shown the grooves 45 2 as terminating short of the lower ends of the slabs, it will be understood that they may open through the slab end.

In building a sewer according to the present invention, I first excavate along the line 50 the sewer is to follow and approximately to

the desired depth. I then force into the soil, at the two sides of the ditch, rows of the slabs 1 to such depth that their lower ends will be below the subgrade 5 of the sewer. The grout 3 may be poured as the successive slabs are 55 placed so that it may set while subsequent operations are being performed. When two rows of slabs have been properly positioned to form the sides of the proposed sewer, they are braced apart by jacks or other 60 devices now commonly employed for similar purposes and excavating then continued to the subgrade 5, whereupon plastic concrete is poured to cover the bottom of the excavation and form a monolithic floor for the sewer, as shown at 6. It will be understood that 65 metallic reenforcing elements may be laid in the floor as the concrete is poured and it will be noted the floor is formed of such thickness that it abuts the under surfaces of the projections 4 which, consequently, resist upward movement of the floor from pressure below while the floor resists downward movement of the sides. After the floor has set, suitable false-work is arranged at the top of the sides and 70 concrete is then poured to form the monolithic top or roof 7, it being noted that ribs or shoulders 8 are formed on the under side of the roof to abut the side slabs and brace the side walls against collapse from pressure of the 75 surrounding earth. As the roof sets, the false-work is withdrawn and the spaces at the sides of and over the sewer are filled in the usual manner.

The slabs 1 are molded and permitted to set 85 before being placed in position and may be cast at a central plant and shipped to the point of use, and, being thus produced under factory conditions can be more cheaply and uniformly made than could be done in the 90 field while contending with mud and water in the ditch. The reinforcements can also be more accurately placed so that thinner slabs may be used. The joints between the slabs are made sand and water tight and the sides 95 are so firmly anchored and braced that even a soft wet earth is held against sliding into the ditch.

While I have particularly described the 100 slabs as constructed with mating grooves 2,

other constructions may be used such as the tongue and groove arrangement shown at 9 in Fig. 4. The edges of the slabs may abut squarely as shown at 10 in Fig. 5 but greater care will then be required to properly seal the joints. Instead of the projections 4, the slabs may have sockets 11 formed therein, as in Fig. 6, so that when the floor is poured it will be automatically keyed to the sides, as indicated 10 at 12 in Fig. 7.

Having fully described my invention what I claim as new and desire to secure by Letters-Patent, is:—

1. A sewer consisting of sides each composed of a plurality of preformed slabs set edge to edge with their lower ends embedded in the ground and the meeting edges sealed, a monolithic floor formed between the sides, and a monolithic roof formed over and carried by the sides.
2. A sewer consisting of sides each composed of preformed slabs of concrete set on end and edge to edge with their lower ends embedded in the ground and their meeting edges sealed, a monolithic cementitious floor formed between the sides and interlocked therewith, and a monolithic cementitious roof formed over and carried by and interlocked with the sides.
3. A sewer composed of sides each consisting of preformed concrete slabs set edge to edge with their lower ends embedded in the ground and their meeting edges sealed and provided above their lower ends with lateral projections, a monolithic floor formed between the sides and abutting the under surfaces of said projections, and a monolithic roof cast on and carried by the sides.
4. The improvement in sewer construction which consists in forcing preformed concrete slabs into the ground in two rows along the line of the sewer to form the sewer side walls, sealing the joints between the slabs, pouring a monolithic cementitious floor between the 45 rows of slabs at a level above the lower ends thereof, the floor uniting with the sides and pouring a monolithic cementitious roof at and across the upper ends of the slabs.

In testimony whereof, I have signed this specification.

ROBERT B. TUFTS.
